CONTROLLING MECHANISM

Filed Feb. 5, 1924

Inventor:

Owen C. From.
by *R. Cottapgood*

Atty.

UNITED STATES PATENT OFFICE.

OWEN C. FROM, OF NEW YORK, N. Y., ASSIGNOR TO WESTERN ELECTRIC COMPANY,
INCORPORATED, OF NEW YORK, N. Y., A CORPORATION OF NEW YORK.

CONTROLLING MECHANISM.

Application filed February 5, 1924. Serial No. 690,707.

To all whom it may concern:

Be it known that I, OWEN C. FROM, a citizen of the United States of America, residing at New York, in the county of New York and State of New York, have invented certain new and useful Improvements in Controlling Mechanisms, of which the following is a full, clear, concise, and exact description.

10 This invention relates to controlling mechanisms and more particularly to those adapted for use in telephone and similar systems.

15 The invention has for its object a new and improved controlling and registering device which is arranged to guard against failures and improper operations.

20 A feature of the invention relates to the provision, in a mechanism where records are registered on one relay register device and then transferred to another register device, of means including contacts on the relays of said first register for determining if the record has been transferred correctly.

25 Other advantages of the present invention will become more clearly understood from the following detailed description and also from the appended claims.

30 Referring to the drawing, the figure illustrates the invention as embodied in a register controlling mechanism for controlling the operation of selector switches in an automatic switching system. At the left of the figure is shown a registering mechanism comprising three separate registers 100, 101 and 102. The register 100 consists of four relays 112 to 115, inclusive, register 101 consists of relays 116 to 119, inclusive, and the register 102 comprises four relay 40 registers 120 to 123, inclusive.

35 At the right of the figure is disclosed a second registering mechanism consisting of three registers 103, 104 and 105. In a similar manner the register 103 comprises four relays 124 to 127, register 104 comprises four relays 128 to 131, while the register 105 includes four relays 132 to 135, inclusive.

40 The central portion of the figure illustrates a part of a connecting device 106 for associating the first set of registers with the second set of registers.

45 The registers 100, 101 and 102 constitute a part of a central office sender which receives digit impulses from a calling subscriber's line or an operator's position. As

is common practice in telephone systems of this character, a plurality of such senders are provided, each having its own set of registers similar to those shown. The incoming series of impulses received by the 60 sender are recorded by operating the relays of the registers 100, 101 and 102 in various characteristic combinations. If the first digit is of a certain character, the relays 112 and 113, for instance, are operated while 65 relays 114 and 115 remain deenergized. If the second digit is of a certain character, relays 118 and 119 are operated, whereas relays 116 and 117 remain inert in response to the second series of impulses. In response to a third series of impulses relays 120, 122 and 123 may be operated, whereas relay 121 remains deenergized.

70 Although only three sets of registers have been shown in connection with the sender illustrated, it will be understood that additional registers may be provided for recording other series of impulses in connection with a designation.

75 The three relay registers 103, 104 and 105 are contained in a controlling mechanism which is separate from the sender and which receives the record set up on the registers 100, 101 and 102 to determine the 80 operation of automatic selecting switches. Here there are also three such registers shown. Register 103 corresponds to the register 100, the register 104 to the register 101 and the register 105 to the register 102. Furthermore, the four relays in each of the latter registers correspond identically to the four relays of each of the registers 100, 101 and 102 in the sender. Inasmuch as there 85 are a plurality of central office senders, it becomes necessary to associate the controlling device at the right of the figure with any particular one of these senders. For 90 this purpose the connecting mechanism 106 is provided. This mechanism consists of a number of multicontact relays 107, 108, etc., each being individual to a separate sender and when operated serving to connect that 95 sender to the controlling device shown.

95 In the operation of a telephone system 105 employing controlling equipment of this character, records are being transferred from the sender registers to the registers in the switch controlling device respectively. Since the correct operation of the system depends upon the accurate transfer of these 110

records, it becomes a desirable matter to have some way of making a check or performing a test on the apparatus each time such a record is transferred in order to determine whether the same is being done correctly. Accordingly, the circuits are so arranged that the register relays 103, 104 and 105, which receive the records from the sender registers, are tested each time a record is transferred, and also the contacts of the connecting device 106 are tested at the same time.

Assume that the registers 100, 101 and 102 are taken into use for recording three sets of impulses. Furthermore, assume that the first set of impulses results in the operation of relays 112 and 114, that the second set of impulses results in the operation of relay 117 and that the third set results in the operation of relays 120, 122 and 123. Following the receipt of this record on the relay registers, the multi-contact relay 107 is operated in any convenient manner to connect the registers 100, 101 and 102 to the registers 103, 104 and 105. At the same time or thereafter, a circuit is closed in any suitable manner for the relay 109. Relay 109 in operating completes a circuit from ground through its contact, contact of relay 110, conductor 137, contacts of relay 107, conductor 138, thence through the back contacts of relays 113 and 115, through contacts of relay 107, windings of relays 125 and 127 to battery. Other circuits lead over the grounded conductor 138, through the back contacts of relays 116, 118 and 119, through contacts of relay 107, windings of relays 128, 130 and 131 to battery. Still another circuit leads over the grounded conductor 138 through the back contact of relay 121, contact of relay 107, winding of relay 133 to battery.

Due to the fact that relays 112 and 114 are operated, a circuit is closed from ground through contact of relay 136, conductor 139, front contacts of relays 112 and 114, thence through contacts of relay 107, windings of relays 124 and 126 to battery. Another circuit leads over conductor 139 through the front contacts of relay 117, contact of relay 107, winding of relay 129 to battery. Still other circuits are traceable over grounded conductor 139, through the front contacts of relays 120, 122 and 123, contacts of relay 107, windings of relays 132, 134 and 135 to battery. Thus, due to the fact that certain of the relays of the registers 100, 101 and 102 are operated, the corresponding relays of the registers 103, 104 and 105 are also operated. The remaining relays of these latter registers are operated in circuits which lead through the connector device 106 and thence through the back contacts of all relays in the registers 100, 101 and 102, which have not been op-

erated as a result of the established registration. In this manner each and every one of the relay registers 103, 104, and 105 are operated whenever a transfer of a record is made in circuits which lead either over the front contacts of operated relays of the sender or over the back contacts of relays which are not operated.

As soon as all of the relays in the registers 103, 104 and 105 are operated, a chain circuit is established from ground, through the contacts of relays 124, 125, 126, 127, 131, 130, 129, 128, 132, 133, 134 and 135, conductor 140, winding of relay 111 to battery. Relay 111 operates and locks through contact of relay 109. Relay 111 at its left contact closes a circuit for relay 110. Relay 110 in operating removes ground from the conductor 137 whereby relays 125, 127, 128, 130, 131 and 133 are released. Thus all relays in the registers 103, 104 and 105 which correspond to unoperated relays in the registers 100, 101 and 102 after having been temporarily operated are again released.

It will be noted that the relay 111 depends for its operation upon the fact that all relays of the registers 103, 104 and 105 have operated. If any of these relays fail to operate due to faulty windings, poor contacts in the connecting device 106 or due to a faulty front contact on one of the relays of the registers 100, 101 or 102, the relay 111 remains inert. Accordingly, the relay 111 may serve to initiate the further operation of the controlling device, consisting of the registers 103, 104 and 105. This indicates that the test shows that a successful transfer of the record has been made and that the apparatus may proceed with its controlling function.

When the equipment is no longer required, relay 107 is released and deenergized, thereby disconnecting the registers 100, 101 and 102 from the corresponding registers 103, 104 and 105. A controlling mechanism of this type is particularly applicable to telephone systems of the character illustrated in the patent to S. B. Williams, No. 1,517,331, issued December 2, 1924.

What is claimed is:

1. In combination, a plurality of register devices for receiving records, electrical contacts on said devices, a second plurality of registers, means for transferring a record from the first registers to the second registers, and means including said contacts for determining if the record has been transferred correctly.

2. In combination, a plurality of registers, each comprising a number of relays for receiving records, a second plurality of registers, each comprising a number of relays, means for transferring a record from the first registers to the second registers,

- and means including back contacts on the relays of said first registers for determining if the record has been transferred correctly.
5. In combination, a register consisting of a number of relays for receiving a record, a second register comprising a number of corresponding relays, means controlled by the operated relays of the first register for operating the corresponding relays of the second register, and means controlled by the unoperated relays of said first register for operating the corresponding relays of the second register to determine if the 10 registration has been correctly transferred from the first register to the second register.
6. In combination, a register comprising a number of relays for receiving a record, a second register comprising a corresponding number of relays for receiving the record from the first register, means controlled by the operated relays of the first register for operating the corresponding relays of the second register, means controlled by the unoperated relays of the first register for operating the corresponding relays of the second register, and means for releasing all relays of the second register which correspond to unoperated relays of the 15 first register.
7. In combination, a register comprising a number of relays for receiving a record, a second register comprising corresponding relays for receiving the record from the 20 first register, means controlled by front contacts of the operated relays of the first register for operating the corresponding relays of the second register, and means controlled jointly by the operated relays of the second register for releasing all relays of such register which correspond to the unoperated relays of the first register.
8. In combination, a register consisting of a number of relays for receiving a record, a second register comprising a corresponding number of relays, a connecting device for interconnecting said registers, circuits controlled over the front contacts of the operated relays of said first register and leading through said connecting device for operating the corresponding relays of the second register, circuits controlled by the back contacts of the unoperated relays of said first register and leading through the connecting device to operate the corresponding relays of said second register, and means controlled jointly by all the operated relays of said second register for causing the release of all relays of the second register which correspond to unoperated relays of the 25 first register.
- In witness whereof, I hereunto subscribe my name this 2nd day of February A. D., 1924.

OWEN C. FROM.
